Ernest Twigg, INVENTOR

Bartlett & Browne, BY ATTORNEYS

UNITED STATES PATENT OFFICE.

ERNEST TWIGG, OF NEW BRITAIN, CONNECTICUT, ASSIGNOR TO LANDERS, FRARY & CLARK, OF NEW BRITAIN, CONNECTICUT, A CORPORATION OF CONNECTICUT.

WRINGER-SUPPORT.

1,378,500.

Specification of Letters Patent. Patented May 17, 1921.

Application filed October 20, 1920. Serial No. 418,269.

To all whom it may concern:

Be it known that I, ERNEST TWIGG, a citizen of the United States, residing at New Britain, county of Hartford, State of Connecticut, have invented certain new and useful Improvements in Wringer-Supports, of which the following is a full, clear, and exact description.

My invention relates to a wringer support 10 in a washing machine and has for its object to provide a securely anchored support which will withstand the strains due to a wringer when mounted thereon.

The following is a description of an embodiment of my invention, reference being had to the accompanying drawing, in which,

Figure 1 shows a section of an embodiment of my invention on the line 1—1, Fig. 3;

Fig. 2 shows a section on the line 2—2, Fig. 1;

Fig. 3 shows a side elevation; and,

Fig. 4 shows a plan view.

Figs. 5 and 6 are perspective details.

Referring more particularly to the drawing, 1 is an upright of the frame of a washing machine having angle-bars 2—2' forming part thereof. 3 is a base block secured to these angle-irons by screws 4 so as to be supported thereby. 5 is a tubular support for a wringer 6, about which the wringer is adapted to swing in the well known manner. This tubular support is secured in the base block by set-screws 7. The strain of the wringer 35 upon this tubular support is very consider-

able and in order to anchor it securely so that it will not yield or injure the framework of the machine, I provide on its lower end an extension 8 of considerable length and surround its lower end by a plate 9 40 forming a socket secured to a right-angled brace 10, one portion of which, 10', is securely riveted to the uprights 1 of the frame.

With this construction, on account of the securing of the lower end 8 of the extended 45 tubular support 5, the upper portion of which is supported and rigidly held by the base plate 3, a strong and durable support for the wringer is attained.

The tubular support is adapted to surround the usual vertical shaft for transmitting power to the wringer.

As will be evident to those skilled in the art, my invention permits of various modifications without departing from the spirit 55 thereof or the scope of the appended claim.

What I claim is:

In a machine comprising a swinging power-driven wringer, the combination of a frame, a base block secured to the upper 60 portion of said frame for supporting the wringer, a tubular member carried by said base block and extending upwardly and downwardly therefrom, a socket secured to said frame below said base block and surrounding the lower end of said tubular member, the upper end of said tubular member being adapted to receive and act as a bearing for said swinging power-driven wringer.

ERNEST TWIGG.
